UNITED STATES PATENT OFFICE

168,239

HEARING AID BATTERY TESTER

William E. Pfeffer, Perkasie, Pa., assignor to Paul Mood, Lester Void, and William E. Pfeffer, co-partners, doing business as The Electro-Mechanical Instrument Company, Perkasie, Pa.

Application August 1, 1952, Serial No. 20,871

Term of patent 14 years

(Cl. D26—5)

To all whom it may concern:

Be it known that I, William E. Pfeffer, a citizen of the United States, residing at Perkasie, in the county of Bucks and State of Pennsylvania, have invented a new, original, and ornamental Design for a Hearing Aid Battery Tester, of which the following is a specification, reference being had to the accompanying drawing, forming a part hereof.

Fig. 1 shows the hearing aid battery tester in front elevation.

Fig. 2 is a side elevation of the battery tester as viewed from the right of Fig. 1, and

Fig. 3 shows the end elevational view of the battery tester.

I claim:

The ornamental design for a hearing aid battery tester, as shown.

WILLIAM E. PFEFFER.
